UNITED STATES PATENT OFFICE.

LOUIS A. CORNELIUS, OF GRAND RAPIDS, MICHIGAN.

CHAIN-POST.

1,054,829.

Specification of Letters Patent.

Patented Mar. 4, 1913.

Application filed January 12, 1912. Serial No. 670,927.

To all whom it may concern:

Be it known that I, LOUIS A. CORNELIUS, a citizen of the United States, residing at Grand Rapids, in the county of Kent and State of Michigan, have invented new and useful Improvements in Chain-Posts, of which the following is a specification.

My present invention relates to chain posts, and its object is to provide an improved and simple device of that character whereby the chain is securely attached to the desired object. This object is attained by, and my invention finds a preferable embodiment in, the chain post hereinafter described, illustrated in the accompanying drawings, in which:

Figure 1 shows my chain post as applied to a bath-tub (shown in fragmentary vertical section) for attaching the upper end of the plug chain to the tub structure: Fig. 2 is an enlarged view partly in central vertical section, of my device shown in Fig. 1: Fig. 3 is a view of the chain post with cap removed: Fig. 4 is a side view of the post's cap: Fig. 5 is a bottom plan view of the same; and Fig. 6 is an edgewise view of the top link of the chain.

In the application of my invention shown, 1 is a bath tub, communicating as shown 30 with the over-flow pipe 2 and having a drain pipe 3 with plug 4, all of any suitable and ordinary form. In my device, the stationary post 5 is provided with an encircling cap 6 adapted to be securely attached there- 35 to, preferably by threading the cap on the post as shown. The cap is laterally recessed at 7 to receive the end link 8 of the plug-chain 9, which link encircles the post near its extremity, in which engagement the link 40 is securely held by the cap. The link 8 is first inserted into the recess 7, after which the cap is attached to the post 5, by turning it as a nut thereon in the construction shown, the end of the post thus entering the 45 link, which encircles it, as shown in Fig. 2.

The post 5 is at its opposite end threaded to a suitable support, as the over-flow pipe

2, and the cap 6 when screwed down im- pings on the interior surface of the bath tub 1 as shown, thus forming a lock-nut 50 whereby both threaded ends of the post 5 are prevented from accidental unscrewing.

It will be seen that, when the parts are in their assembled position shown in that figure, the link 8 is securely held and cannot 55 be disengaged from the post 5 so long as the cap remains in such position: it will also be seen that the hanging position of the chain prevents the accidental unscrewing of the cap, and that inasmuch as the recess 7 opens 60 downwardly only, it will keep clean and drained, which is very desirable in bathtubs and the like.

Not confining myself to the details of construction shown and described, I claim: 65

1. In a device of the character described, a support, a horizontally disposed post fastened to the support and having an encircling cap adapted to be securely attached to the post and having a lateral recess on its 70 under side, and a chain link adapted to enter said recess and to encircle the post in the attached position of the cap.

2. In a device of the character described, a post having a screw cap threaded thereon 75 provided with a lateral recess, and a chain link adapted to enter said recess and to encircle the post in the screwed-on position of the cap.

3. In a device of the character described, 80 a support, a post threaded at one end on the support, a lock nut for said threaded connection and threaded on the post at the opposite end and provided with a lateral recess, and a chain link adapted to enter said 85 recess and to encircle the post in the screwed-on position of the cap.

In testimony whereof I have hereunto set my hand in presence of two subscribing witnesses.

LOUIS A. CORNELIUS.
